COMBINED SOFA BED AND END TABLE

Louis Elliott Frey, Los Angeles, Calif.

Application March 28, 1957, Serial No. 45,474

Term of patent 14 years

(Cl. D5—4)

Fig. 1.

Fig. 2.

Fig. 3.

Fig. 1 is a perspective view showing a combined sofa bed and end table embodying my new design, with the sofa bed in closed position;

Fig. 2 is a perspective view of the same, with the bed in open position;

Fig. 3 is a side elevational view of the same, with the bed in closed position.

I claim:

The ornamental design for a combined sofa bed and end table, substantially as shown.
